DOOR MOUNTING

Wesley A. Smith, Ferndale, Mich., assignor to
 Tilt-A-Door Corporation, Detroit, Mich., a corporation of Michigan

Application December 6, 1949, Serial No. 131,290

11 Claims. (Cl. 20—16)

1

This invention relates in general to a device for mounting a substantially one piece garage door upon a door frame, and more particularly to a type of door mounting device having means for pivotally supporting said door upon said door frame about a horizontal axis.

It has been found that presently known types of one piece, counter-weighted, garage doors fabricated from light materials, such as aluminum, plastic and plywood, and installed for opening and closing by pivotal movement thereof about a horizontal axis, do not have sufficient structural strength, especially under conditions of frequent and/or rough usage, to be mounted upon a door frame by means of pins secured to the vertical edges thereof. Often, such a door will become bent about the axis of said pivot pins or become otherwise warped under vigorous operating conditions. Such warping becomes particularly evident where the door is used in commercial operations, or where its expanse is fairly large, such as in a one piece door for a double garage. One of the major causes for failure seems to be that the counterweight used in such doors is too heavy to be entirely supported by the door panels, which panels, as presently constructed, are pivotally supported upon the door frame.

Another problem in the installation of garage doors arises from the fact that the vertical door jambs are sometimes not parallel with each other. Furthermore, it has been found that in order to close the door tightly against said jambs, it is desirable to have that vertical door edge remote from the door lock contact its jamb first. Thus, it becomes highly desirable to provide a door having means whereby it can be adjustably and controllably distorted out of a true planar condition with relative ease at the time and place of installation. To provide a structure capable of being so distorted or twisted, but then capable of strongly resisting further or return twisting, has thus long been a highly desirable, but unattained insofar as I am aware, objective in the manufacture of garage doors.

Accordingly, a primary object of this invention is the provision of a sturdy, substantially integral, door mounting device upon which the panels of a one piece garage door may be secured, and which will support the counterweights necessary for satisfactory operation of the door independently of the door panels.

A further object of this invention is the provision of a door mounting device, as aforesaid, which can be adjusted to impose a predetermined distortion, or warpage upon the door panel and

which has means secured thereto for supporting said mounting device and the door panel secured thereto upon a door frame for pivotal movement about a horizontal axis.

5 Another object of the invention is to provide a door capable of accomplishing the foregoing objectives without requiring such great strength and resultant weight in the door panel that it becomes unreasonably expensive to make or

10 heavy to use.

Another object of this invention is to provide a door, as aforesaid, in which a strong, relatively small, warpable, steel hanger is provided to support a relatively lightweight door panel and 15 in which a counterweight supporting means is utilized both as an integral part of the hanger and as a means to hold the door in an adjusted warped, position.

Other objects of this invention will become 20 apparent to persons familiar with this type of structure upon referring to the accompanying drawings and upon reading the following specification.

In meeting those objects heretofore mentioned, 25 as well as others incidental thereto and associated therewith, I have provided a tubular beam having a substantially rectangular cross-section and a pair of parallel coextensive support arms adjustably secured at one end of each to the 30 opposite ends of said beam, said arms extending in a direction substantially perpendicular to the longitudinal axis of said beam and in substantially the same direction therefrom. A pair of co-axial pivot pins are secured to said 35 arms at points thereon equally and adjustably spaced from said beam and extending from the remote sides of said arms, for pivotal support of the mounting device upon a door frame. The door panel is mounted upon and supported by 40 said beam and said arms.

For illustration of a preferred embodiment of this invention, reference is made to the accompanying drawings in which:

Figure 1 is a broken, front elevation view of 45 the door mounting device to which this invention relates including a broken line showing of a portion of the door panel mounted thereon.

Figure 2 is a broken, side elevation view of a door including said door mounting device.

Figure 3 is a sectional view taken along the line III—III of Figure 1.

Figure 4 is a sectional view taken along the line IV—IV of Figure 3.

Figure 5 is a sectional view taken along the line V—V of Figure 1.

Figure 6 is a sectional view taken along the line VI-VI of Figure 4.

Figure 7 is a perspective view of a fragment of said door in a horizontal position.

Figure 8 is a perspective view of a fragment of said door in a vertical position and shows an alternate door hanger.

Figure 9 illustrates a modified construction in the region where the door panel is fastened to the counterweight beam.

As shown in Figures 1, 3 and 4, the door mounting device 10 is comprised of an elongated, hollow, counterweight beam 11, which also functions as a torque tube, having left and right support arms 12 and 13, respectively, secured at the upper end of each to the opposite ends of said beam 11 in a manner hereinafter described in detail.

For convenience in description the terms "left" or "leftwardly" and "right" or "rightwardly," as used in this specification, shall be understood to mean leftwardly and rightwardly of the mounting device, or parts thereof, when positioned as appearing in Figure 1. The terms "upper" or "upwardly" and "lower" or "downwardly" shall have reference to the mounting device when positioned to effect a door closure (Figure 1). The terms "outside" and "inside" shall have reference to the geometric center of the mounting device.

The beam 11 (Figures 1, 3 and 4), which may be constructed in any conventional manner, is preferably fabricated from heavy gauge sheet metal, such as steel, of sufficient strength to support the counterweights 14 placed therein, and comprises an upper wall 15, a lower wall 16, a front wall 17 and a rear wall 18. The front and rear walls, 17 and 18, respectively are on the front and rear sides of the door assembly 19, when in the closed position within a door frame. The lower wall 16 of the beam 11 (Figure 3) is preferably provided with a securing flange 21 extending downwardly from the front edge of the lower wall 16 and parallel with, and adjacent to, an extension of the lower edge of the front wall 17. The flange 21 may be secured to said extension of the front wall 17 in any convenient, conventional manner, such as by welding or bolting.

The left and right support arms 12 and 13, respectively, are advantageously, but not necessarily, mirror images of each other and are secured to opposite ends of the beam 11 preferably in identically the same manner. Accordingly, the following description of the left support arm 12, and the manner and means for securing thereof to the beam 11, shall be understood to apply in substance to the right support arm 13.

The left support arm 12, which is preferably fabricated from a structural angle (Figures 3, 4 and 5), comprises a long flange 22 and a short flange 23. The left arm 12 is positioned with respect to the leftward end of the beam 11 (Figure 4) so that the long flange 22 bears against the leftward ends of the walls of the beam 11 and is substantially perpendicular to the longitudinal axis of the beam 11, and, further, so that the short flange 23 is substantially parallel with, and adjacent to, the outside surface of the rear wall 18.

The first flange 24 of a structural angle 25 (Figure 4) is secured to the inside surface of the front wall 17 of the beam 11 in any convenient manner, as welding, so that the outside surface of the second flange 26 of said angle 25 lies substantially within a plane defined by the leftward

ends of the walls of the beam 11. Thus, when in proper position, the long flange 22 of the left arm 12 is substantially parallel with and adjacent to the outside surface of the second flange 26.

A sheet metal end cap 27 is shaped to extend from the rear wall 18 around the free end of the short flange 23 along the outside surfaces of both the short and long flanges 23 and 22, respectively, and terminates with a panel support flange 28 substantially parallel with and extending leftwardly from, the front wall 17 of the beam 11.

The short flange 23, the adjacent portion of the end cap 27, and an elongated, metal rear shim 33, which may be provided along the short flange 23 against the outside surface of the end cap 27, are secured to the rear wall 18 preferably by means of the upper and lower rear bolts 31 and 32, respectively. The rear shim 33 is provided to strengthen the securing of the end cap 27 upon the short flange 23. The bolt openings in the rear wall 18 and the rear shim 33, through which the bolts 31 and 32 extend, are preferably circular and just large enough to slidably receive the bolts 31 and 32. However, the short flange 23 and that portion of the end cap 27 adjacent thereto are provided with vertically elongated, adjustment slots 34 and 35 for slidable and vertically adjustable reception of the bolts 31 and 32, respectively, therethrough. Accordingly, it is apparent from Figure 6 that when the bolts 31 and 32 are loosened, the short flange 23 and that portion of the end cap 27 adjacent thereto may be moved upwardly and downwardly with respect to the rear wall 18 and the rear shim 33.

The long flange 22 of the arm 12 is secured to the second flange 26 of the structural angle 25 by means of the upper and lower side bolts 36 and 37, respectively. The second flange 26 and a side shim 38, similar to the rear shim 33 and disposed on the outside of that portion of the end cap 27 adjacent to the long flange 22, are preferably provided with circular openings through which the bolts 36 and 37 may pass. The long flange 22 and adjacent portion of the end cap 27 may be provided with an over-sized opening 39 through which the upper side bolt 36 extends, thereby permitting rotational movement of said long flange 22 and the adjacent portion of the end cap 27 about the lower bolt 37 and with respect to the side shim 38 and the second flange 26 when the side bolts 36 and 37 are loosened.

Accordingly, it will be observed that the adjustment slots 34 and 35 and the oversized opening 39 permit adjustability of the left support arm 12 about the longitudinal axis of the beam 11 and within a plane substantially perpendicular thereto.

The lower end of the long flange 22 extending downwardly from the counterweight beam 11 is provided with one or more circular pivot pin openings 41 through which the left pivot pin 42 may extend leftwardly from the long flange 22.

As illustrated in the drawings, the pivot pins 42 and 42a are mounted in the lowermost pair of openings 41 and 41a in the flanges 22 and 22a, respectively.

By mounting said pins in a higher pair of openings, and by increasing the counterweight within the beam 11, the same door may be used in a door frame having a higher clearance. Said pivot pin 42 may be adjustably secured to the long flange 22 by means of adjustment shoulder nuts 43 and 44 (Figure 5). A pivot pin shim 45 may be placed along the outside surface of the end cap 27 for strengthening the support thereof.

upon the long flange 22. The left pivot pin 42 may be rotatably supported upon and within a cylindrical bracket 46, which bracket may be secured in any conventional, convenient manner upon the vertical side jamb 47 of a door frame (not shown).

The right pivot pin 42a is identical with the left pivot pin 42, in this embodiment, and is secured to the long flange 22a of the right support arm 13 in identically the same manner as is the left pivot pin 42 and is coaxial with said left pivot pin.

The precise manner in which the door panel, or panels, 48 are secured to the beam 11 and support arms 12 and 13 may be varied substantially within the scope of this invention. In this embodiment, the vertical edges of the door panel 48 are folded around the free edges of the panel support flanges 28 and 28a (Figures 1 and 4) of the end caps 27 and 27a. The upper edge of the front wall 17 of the beam 11, is folded downwardly upon itself and then bent around and upwardly behind the securing flange 21 of the lower wall 16. The bent portion 50 of the panel 48 may be secured to the securing flange 21 by any convenient means, such as the screws 51. As an alternative to the method of effecting this securing by the screws 51, the bent portion 50a (Figure 9) may be sprung to grip frictionally said flange 21. The wall 17 of the beam 11, the panel support flanges 28 and 28a of the end caps 27 and 27a, and the door panel 48 (Figure 1) all cooperate to provide the front surface of the door assembly 19.

An elongated access opening 52 may be provided in the front wall 17 for the purpose of inserting the counterweights 14, which in this particular embodiment of the invention may be standard building brick, within the counterweight beam 11. Accordingly, the proper amount of counterweight can be fully and readily adjusted to the particular application.

Operation

It will be seen from the above description, that the left and right support arms 12 and 13 are rigidly, but adjustably, secured to opposite ends of the counterweight beam 11 and that the pivot pins 42 and 42a are rigidly, but adjustably, secured to the left and right support arms 12 and 13, respectively. Thus, the counterweights 14 within the beam 11 are supported entirely independently of the door panel 48, which is in turn supported upon the beam 11 and support arms 12 and 13.

The necessary distortion, or warping, of the door panel 48 may be easily accomplished by loosening the rear bolts 31 and 32 and the side bolts 36 and 37 at either or both ends of the beam 11 and then rotating either or both of the support arms 12 and 13 about the lower side bolts 37 and 37a (Figures 2 and 3) within planes substantially perpendicular to the longitudinal axis of the beam 11. When the appropriate distortion has been accomplished, the rear and side bolts are then tightened and the door assembly 19 is ready for operation.

In this way the hollow beam 11 functions as a torque tube which is sufficiently rigid to resist the tendency of the warped panel to rotate the support arms, bolted thereto, back to the positions they held before the warp was imposed upon the panel. Tests have shown that this structure provides strength far beyond anything with which I have been familiar prior hereto. For example,

with the door in a horizontal position, a person may suspend his entire weight from one corner thereof without destroying the adjustment of the door or otherwise distorting it.

By supporting the counterweight on the steel of the support arms, rather than upon the material of the door, and by holding the support arms in an adjusted position by bolting them to the beam 11, there is provided an extremely strong, self-contained unit for supporting a door panel whereby none of the weight of the counterweight nor the stress imposed upon the beam by the warped panel is borne by said door panel. Thus, an extremely light door panel may be used, thereby promoting both an ease of handling and an economy of fabrication without sacrifice of strength or durability.

Although the above mentioned drawings and description apply to one particular preferred embodiment of the invention, it is not my intention, implied or otherwise, to eliminate other variations or modifications which do not depart from the scope of the invention unless specifically stated to the contrary in the hereinafter appended claims.

I claim:

1. In a counterweight supporting structure for supporting a garage door, the combination comprising: an elongated, hollow beam of substantially rectangular cross-section; an angular support arm at each end thereof, each including a first flange positioned perpendicularly to the longitudinal axis of the beam and a second flange perpendicular to said first flange and lying closely against one face of said beam; means defining openings in said second flange and said face, said openings being in register and one being elongated in a direction transverse of said beam; a bolt through said openings and a nut thereon holding said second flange tightly against said face; an angle member having one leg adjacent to that face of said beam opposite said one face and having another leg adjacent to said first flange, openings through one of said legs and the member adjacent thereto, said openings being in register and one of said openings being elongated in a direction transversely of said beam; a bolt through said openings and a nut thereon holding said one leg releasably affixed to the said member adjacent thereto; axially aligned pivot pins on said support arms at points thereon spaced from said beam and extending oppositely to each other; and said beam and said arms being adapted for supporting a door panel; whereby upon loosening of said nuts said support arms may be rotated about the axis of said beam for warping said door panel, and upon retightening of said nuts said beam and said arms will hold said panel in said warped position in addition to receiving and holding within said beam a plurality of counterweight elements.

2. The device claimed in claim 1 wherein the angle member is permanently affixed to the face of said beam opposite said one face thereof and is affixed as described in claim 1 to the first flange of said support arm.

3. In a garage door pivotally supported about a horizontal axis upon a door frame, the combination comprising: an elongated, hollow steel beam having a rectangular cross-section, and adapted to receive counterweight means therewithin; an integral door panel having side frame members; a pair of parallel coextensive, steel arms independent of the door panel; means securing one end of each of said arms to opposite

ends of said beam, said arms being substantially perpendicular to the longitudinal axis of said beam and extending in the same direction therefrom and being adjustable about said axis, said means being loosenable to permit limited rotation of said arms about an axis within and longitudinal of said beam; means mounting said door panel upon said beam and said arms with said side frame members adjacent to and parallel with said arms, said panel being slightly distortable by said limited rotation of said arms with respect to said beam; and a pair of coaxial pivot pins secured to, and extending from, the remote sides and other ends of said arms for pivotal support upon said door frame.

4. In a garage door, pivotally supported for rotation about a horizontal axis upon a door frame, the combination comprising: an elongated, hollow, steel beam having a rectangular cross section and adapted to receive counter weight means therein; a pair of parallel, co-extensive, steel arms, each thereof secured at one of their respective ends to the respectively opposite ends of said hollow beam, and the other end of each of said arms having a pivot pin, said arms extending parallel with respect to each other and in the same direction from said steel beam and said pivot pins extending oppositely to each other; a pair of aluminum side frame elements closely overlaying each of said steel arms and means affixing said side frame elements to each of said respective steel arms; a door panel mounted on and supported by said aluminum side elements.

5. In a counterweight supporting structure for supporting a garage door, the combination comprising: an elongated, hollow beam of substantially rectangular cross section; a support arm at each end thereof, each support arm including a first flange positioned perpendicularly to the longitudinal axis of said beam and a second flange positioned perpendicularly to said first flange and lying closely against one face of said beam; means defining openings through said second flange, said openings being in register, and one being elongated in a direction transverse of said beam; releasable fastening means extending through said openings for holding said second flange tightly against said face; an angle member having one leg adjacent to that face of said beam opposite said one face and having another leg adjacent to said first flange, openings through one of said legs and the member adjacent thereto, said openings being in register, and one of said openings being elongated in a direction transversely of said beam; releasable fastening means extending through said openings for holding said one leg releasably affixed to the said member adjacent thereto; means affixing said other leg to the member adjacent thereto; axially aligned pivot pins on said support arms at points thereon spaced from said beam, said beam and said arms being adapted for supporting a door panel.

6. In a garage door pivotally supported about a horizontal axis upon a door frame, the combination comprising: an elongated hollow steel beam having a rectangular cross section, and adapted to receive counterweight means therewithin; a pair of parallel, co-extensive steel arms; means securing one end of each of said arms to opposite ends of said beam, said arms being substantially perpendicular to the longitudinal axis of said beam and extending in the same direction therefrom, and said means permitting limited rotation

of said arms about the said longitudinal axis of said beam; releasable means holding said arms fixedly with respect to said means; a panel secured to and supported upon said beam and said arms, said panel being slightly distortable by limited rotation of said arms with respect to said beam; a pair of co-axial pivot pins secured to and extending from the remote sides and other ends of said arms for pivotal support upon said door frame.

7. In a garage door pivotally supported in a door frame about a horizontal axis the combination comprising: an elongated counterweight beam; a pair of steel arms positioned respectively adjacent each end of said beam; means mounting each of said arms to said beam and permitting pivotal movement of each of said arms with respect to said beam substantially on the central axis of said beam; means clamping said arms in a selected position with respect to said beam; pivot means on said arms at points thereon spaced from said beam, said pivot means being co-axial with each other and adapted for reception by support means arranged on said frame; a door panel having side frame members, said frame members lying parallel with, and adjacent, each of said arms respectively and an edge of said panel between said side frame members positioned adjacent said beam; means fastening each of said side frame members respectively to said adjacent ones of said arms.

8. In garage door construction, for providing a door swingable on a horizontal axis and supported on a door frame, the combination comprising: a panel; a frame-work for supporting said panel comprising a beam, a pair of arms extending respectively from each end of said beam and a pair of pivot means positioned respectively on each of said arms at points thereon spaced from said beam, said pivot means being adaptable for pivotal support in said frame, said arms being affixed to said beam for limited pivotal movement with respect thereto and means clamping said arms in a selected position with respect to said beam; means mounting said panel onto said arms adjacent said beam.

9. In a counterweight supporting structure for supporting a garage door, the combination comprising: an elongated beam of substantially rectangular cross section; an angular support arm at each end thereof, each arm including a first flange positioned perpendicularly to the longitudinal axis of the beam and a second flange perpendicular to said first flange and lying closely against one face of said beam; clamping means holding said second flange tightly against said face; an angle member having one leg adjacent to that face of said beam opposite said one face and having another leg adjacent to said first flange; clamping means holding one of said legs and the member adjacent thereto fixed with respect to each other; co-axially positioned pivot pins respectively on each of said support arms at points thereon spaced from said beam; whereby upon loosening of said clamping means said support arms may be rotated about the axis of said beam for warping said door panel and upon re-tightening of said clamping means said beam and said arms will hold said panel in said warped position.

10. In a closure pivotally supported in a frame about a horizontal axis the combination comprising: an elongated counterweight beam; a pair of metallic arms positioned respectively adjacent each end of said beam; means mounting each of

said arms to said beam and permitting pivotal movement of each of said arms with respect to said beam substantially on the central axis of said beam; means clamping said arms in a selected pivotal position with respect to said beam; pivot means on said arms at points thereon spaced from said beam, said pivot means being co-axial with each other and adapted for reception by support means arranged on said frame; a panel having a pair of side frame members, said frame members each lying adjacent each of said arms respectively and an edge of said panel between said side frame members positioned adjacent said beam; means fastening each of said side frame members respectively to said adjacent ones of said arms. 15

11. In closure construction, for providing a closure swingable on a horizontal axis and supported on a frame peripherally surrounding said closure, the combination comprising: a panel; a 20 frame-work for supporting said panel comprising

5
10

a beam, a pair of arms extending respectively from each end of said beam and a pair of pivot means positioned respectively on each of said arms at points thereon spaced from said beam, said pivot means being adaptable for pivotal support in said frame, said arms being affixed to said beam for limited pivotal movement with respect thereto and means clamping said arms in a selected position with respect to said beam; means mounting said panel onto said arms adjacent said beam.

WESLEY A. SMITH.
